O. ELLIS.

Machine for Mortising Window Sashes.

Patented January 16, 1834.

Jan. 16, 1834

5

Oren Ellis, of Orange, Mass.

Letter Patent

7965

The scheme is referred to in these Letters Patent and making part of the same containing a description in the words of the said Oren Ellis himself, of his improvement, in the machine for mowing and binding grass, and that the following is a full and exact description of the construction and operation of the said machine, as invented by me.

Set out two upright main posts with stands, of any convenient size and of a convenient height, secured at the top, by a horizontal cross beam of a suitable size and length (with mortises) and also secured at the bottom about nine inches from the stands, by another cross beam uniting the parts by tenons in the end of it, and mortised in the parts, so there be also an upright post of suitable dimensions with a projection at the top for the purpose of receiving the upper end of a prop for a lever to be hereafter described. The last mentioned post should be placed perpendicular between the upper and lower horizontal posts, at any convenient distance from the left hand side of the centre of the horizontal beams, tenoned at each into the horizontal beams.

Set there be also an iron or wood prop of suitable dimensions with a hole at the upper end to receive a bolt at the aforesaid projection placed on the surface of the last mentioned upright post on the back side, and extending down through the lower horizontal cross beam about six inches with a succession of holes in the part that extends below the lower horizontal cross beam for raising and lowering the shank hereafter to be described.

Let there be also a lever of convenient length and size, uniting to the prop with a bolt, which extending to the right of the right hand main post, through an aperture made in the right hand main post extending down from the lower cross beam to the stand thereof. There should be a steel or wood spring secured to the upper cross beam by means of otherwise upon the outer side thereof and extended to the right hand main post at the right hand end of which let fall a small cord passing down through a hole made in the lower cross beam and attached to the lever, so that when the lever is pulled down the prop will draw it back to its original position.

or the same effect may be produced by attaching a weight to a pulley fixed on the under side of the upper cross beam; also let there be a slide post of any convenient size sufficient to give it strength. This slide post is to pass perpendicular through the centre of each of the horizontal cross beams; mortises being made in the said beams sufficiently large to admit the slide post and extending down through the lower cross beam and united to the lever by a tenon inserted in a loose mortise in the lever, and secured by a bolt. The slide post is also to extend up above the upper cross beam sufficiently high to affix a stock for chisel so that when the slide post is thus placed, it will move down and up by the operation of the lever. — Another part of the machine is what is called a rest or fence of any suitable length, longer than the upper cross beam for the purpose of giving space to receive the piece to be mortised. There should be notches or gains made in the rest from each end of it, nearly to the slide post for the accommodation of movable stops on each side of the slide post. The fence or rest is to be placed and secured fast on the upper side of the upper cross beam, lying on the surface upon the longitudinal centre, the sliding post passing up through it through a mortise. In the notches or gains on each side of the slide post, there should be movable stop, for the ends of the pieces to rest against which is mortised. — Another part of the machine consists of a stock and chisel, which are designed to perform the works of mortising, described and placed as follows. Set there be a cast iron stock of about nine inches long, with a hole at the upper end and one at the upper end of the projection, to be described, to receive bolts to fasten it to the slide post. There should be a sufficient projection at the lower end of the stock, with four grooves, one on each side of the projection, for the insertion of the chisel. The projection of the stock should be sufficient to carry the chisel out directly over the place where the mortise is to be made in the piece when it is put against the rest or fence. There should be four chisel of any size sufficient to make the mortise, placed and made fast in the grooves of the projection of a stock by means of an iron band, passing around the projection with screws bearing upon these parts of the chisel which are in the grooves. The whole length of the chisel should be five or six inches, or more if necessary, bent in at the lower ends and brought round it such a manner as to give the form and size, which the mortise requires, and secured by another iron band around them about three fourths of an inch from the edges of the chisel with an iron strap connected with the band, and extending up under the upper band, and then secured by a screw to prevent it sliding down.

7

over the edges of the chisels. There should be a perpendicular aperture through the projection of the stock, for the purpose of receiving a wrought iron punch, to fit the space formed between the chisels when inserted in the grooves of the stocks, and to clear that space of chips, in the operation of the machine. There should be an upright support attached to the rest or fence by a screw, and extending up the left hand side, of the slide post, having an arm around the slide post with a hole through the end of the arm to receive the upper end of the punch. The upper end of the punch should be a screw. The stock with the chisels is to be placed & fasten upon the front side of the slide post at any convenient distance above the upper cross beam to give room under the edges of the chisels for the piece to be mortised — —

The end of the punch which is a screw is to pass through the hole in the end of the arm of the upright support having ^{nut} cuts above and below the arm of the upright support and contiguous to the arm, so that in the operation of the lever the punch will perform its office of clearing the chisels of chips when the chisels rise. The chisels may be united in one taking the same form at the lower end, as the four do when separated, or one chisel may be used made in the form of a hollow square at the lower end with a shank to bolt it to the stock. The whole machine is designed to be operated by foot power, water power, or steam power — —

What is claimed as an invention is an invention of a square chisel set in a stock and having a punch or cleare operating within the same, for mortising window sashes — —
